PHOTOGRAPHIC FILM PROCESSOR OR SIMILAR ARTICLE

Henry F. Hope and Stephen F. Hope, both of 195 Welsh
Road, Huntingdon Valley, Pa. 19006

Filed Mar. 18, 1970, Ser. No. 21,962

Term of patent 14 years

Int. Cl. D16—06

U.S. Cl. D61—1

FIG. 1

FIG. 2

FIG. 3

FIG. 4

FIG. 5

FIG. 6

FIG. 1 is a perspective view of a photographic film processor or similar article showing our new design;

FIG. 2 is a left end elevational view thereof;

FIG. 3 is a right end elevational view thereof;

FIG. 4 is a front elevational view of FIG. 1, the opposite side being a mirror image thereof;

FIG. 5 is a top plan view thereof; and

FIG. 6 is a bottom plan view thereof.

We claim:

The ornamental design for a photographic film processor or similar article, substantially as shown and described.
